D3-4

AU 292

EX

XR D 18,951

DESIGN.

D. L. CLINTON.

RECEIVING CARD.

No. 18,951.

Patented Mar. 12, 1889.

Fig. 1

Fig. 2

Fig. 3

WITNESSES:

Mary E. Barnes
Lime Barnes Jr.

INVENTOR

BY David Lawrence Clinton
George G. Barnes

ATTORNEYS

UNITED STATES PATENT OFFICE.

DAVID LAWRENCE CLINTON, OF CLINTONVILLE, CONNECTICUT.

DESIGN FOR A RECEIVING-CARD.

SPECIFICATION forming part of Design No. 18,951, dated March 12, 1889.

Application filed December 22, 1888. Serial No. 294,429. Term of patent 3½ years.

To all whom it may concern:

Be it known that I, DAVID LAWRENCE CLINTON, a citizen of the United States, residing at Clintonville, in the county of New Haven and State of Connecticut, have invented and produced a new and original Design for a Receiving-Card, of which the following is a specification, reference being had to the accompanying drawings, forming part thereof.

Figure 1 is a face view of my newly-designed calling or receiving card. Fig. 2 shows edge views or side elevations of the same, and Fig. 3 is an edgewise sectional view through the center of the card, which views fully illustrate the novel features of my design.

This design consists, essentially, of a sector-shaped card formed to resemble an open fan and having a raised ornamental border mounted upon its face, extending around the curved edge thereof, as hereinafter more fully described and claimed.

Referring to the drawings, A represents the card, which is shaped like a sector of a circle, in imitation of an open fan. Upon the face side of the card, or side upon which the name is to be written, a raised ornamental border extends around the curved edge of the card, so that it constitutes a portion of the surface thereof, which surface is thus raised above the remaining portion of the face of the card. The ornamental border and the surface of the card are ornamented to represent a fan, a smooth panel or area being left near the center thereof to receive a name.

I claim—

The design for a calling or receiving card, consisting, essentially, of a sector or fan shaped card ornamented to represent a fan, with the central space or panel to receive the name, and having a raised ornamental border extending in an arc of a circle around the curved edge of the sector, forming part of the surface configuration of the same, substantially as herein described and shown.

DAVID LAWRENCE CLINTON.

Witnesses:

B. A. CULVER,
EDWARD L. LINSLEY.